[57] **CLAIM**

The ornamental design for a combined fat and oil separator and stand therefor as shown, and described

DESCRIPTION

FIG. 1 is an exploded perspective view of a combined fat and oil separator and stand therefor showing my new design; FIG. 2 is a front elevation view of the separator shown separately for clarity of illustration;

FIG. 3 is a rear elevation view of FIG. 2;

FIG. 4 is a right side elevation view of FIG. 2;

FIG. 5 is a left side elevation view of FIG. 2;

FIG. 6 is a top plan view of FIG. 2;

FIG. 7 is a bottom plan view of FIG. 2;

FIG. 8 is a front elevation view of the stand portion shown separately for clarity of illustration, the opposite side being a mirror image;

FIG. 9 is a right side elevation view of FIG. 8, the opposite side being a mirror image;

FIG. 10 is a top plan view of FIG. 8; and,

FIG. 11 is a bottom plan view of FIG. 8.
